UNITED STATES PATENT OFFICE.

WILLIAM H. LOSE, OF ZELIENOPLE, PENNSYLVANIA, ASSIGNOR TO IRON CITY SANITARY MANUFACTURING COMPANY, OF PITTSBURG, PENNSYLVANIA, A CORPORATION OF PENNSYLVANIA.

LEG FOR BATH-TUBS.

938,066.

Specification of Letters Patent. Patented Oct. 26, 1909.

Application filed March 30, 1909. Serial No. 486,683.

To all whom it may concern:

Be it known that I, WILLIAM H. LOSE, a resident of Zelienople, in the county of Butler and State of Pennsylvania, have invented a new and useful Improvement in 5 Legs for Bath-Tubs, and do hereby declare the following to be a full, clear, and exact description thereof.

My invention relates to legs for bath-tubs 10 and has special reference to a fastening for the attachment and securing of the leg to the tub.

The object of my invention is to provide a cheap, simple and efficient means for the 15 connecting of the leg to the tub, whereby such leg can be easily and quickly attached and secured in position, as well as such a means which will rigidly and firmly hold the leg in place when in position, and will 20 not be liable to permit the leg to turn, swing, move or become detached when duly set or connected to the tub.

My invention consists, generally stated, in the novel arrangement, construction and 25 combination of parts, as hereinafter more specifically set forth and described and particularly pointed out in the claims.

To enable others skilled in the art to which my invention appertains to construct 30 and use my improved leg for bath-tubs, I will describe the same more fully, referring to the accompanying drawing, in which—

Figure 1 is a vertical section of a bath-tub leg and a portion of the tub with my invention applied thereto. Fig. 2 is an inner face 35 view of the leg, partly in section, and showing a portion of the tub in section. Fig. 3 is a horizontal section on the line 3—3 Fig. 1 and looking in the direction of the arrow. 40 Like symbols of reference herein indicate like parts in each of the figures of the drawing.

As illustrated in the drawing, 1 represents a portion of the ordinary form of a bath-tub, and 2 the bottom of the same having the usual curved portion 3 extending outwardly therefrom. Projecting down from the under face of the bottom 2 and integral therewith is a cored lug or hanger 4, which is 45 provided with the central body portion 5 below said bottom and connected thereto by the side portions 6, and with the curved or rounded outer end portion 5' extending beyond said side portions. Projecting below

the under face of the body portion 5 and in 55 line with the side portions 6 are the lugs or bearing portions 7 and within said body portion is a nut 8 which is located centrally of the same and secured therein in any suitable manner.

The leg 9 is of the usual shape and has a shelf or tongue plate 10 formed integral therewith and projecting out from the inner face of the same. This plate 10 is provided with a recessed or socket portion 11 in the 65 upper face of the same and with a hole 12 extending through the same at such recessed or socket portion and through the body 10' of said plate. The free or outer portion of the plate 10 in forming the outer end wall 70 for the recessed or socket portion 11 is cut-away centrally of said plate, as at 13' to form the members or stops 13 on each side of such plate, which project inwardly from the side walls of said recessed or socket portion on the body 10' and permits the curved outer end portion 5' on the hanger to extend 75 between said stops.

When the leg 9 is to be attached to the tub 1 the hanger 4 on the bottom 2 of said tub 80 is placed within the recessed or socket portion 11 in the plate 10 on said leg, and a tap bolt 14 is then inserted through the hole 12 in said plate so that its threaded portion 15 can engage with the nut 8 in said hanger. 85 When screwed to place the head 16 on the nut 8 can bear against the under face of the plate 10 and the upper end 9' on the leg 9 will bear against the curved portion 3 on the tub 1, while the hanger 4 will be seated 90 within the recessed or socket portion 11 in said plate by its lug portions 7 bearing against the body 10' of such plate and the side portions 6 and lug portions 7 bearing against the stops 13 at the outer end of said 95 plate. It will thus be seen that my improved leg for bath-tubs provides for a means of attaching the same to the tub that is composed of few and simple parts and will enable the easy and convenient assembling of 100 these parts together for securing the leg in position. The manner of securing the leg to the tub will enable such leg to be held in position at all times, so that the upper end of the leg will be held and bear against the 105 tub and in its proper position, even though the tap-bolt may be dispensed with or become loosened or separated from its engag-

ing parts, by the hanger on the tub being seated in the socket in the plate and engaging with the stop or abutments on the outer portion of the leg plate, while the inner end wall of the socket in such plate will also engage with such hanger and stop any movement of the hanger away from such abutments. Sufficient side movement between the side walls of the seat is also permitted 10 for the hanger in case of such loosening or separation of the parts and for the proper positioning of the parts for the engagement of the tap-bolt with the hanger.

The attaching parts are strong and durable, are easily cast on the tub and leg and the leg can be readily and quickly detached from the tub at any time and when desired for any purpose. The device will not be liable to get out of order or permit the leg 20 to become separated from the tub by the loosening or removal of the tap-bolt and will form a rigid and strong connection at all times.

It will be obvious that my improved fastening can be used with vessels or other articles than bath-tubs, such as sinks, wash-stands, etc., and various other modifications and changes in the design and use of the same may be resorted to without departing 30 from the spirit of the invention or sacrificing any of its advantages.

What I claim as my invention and desire to secure by Letters Patent, is—

1. A fastener for the legs of bath-tubs comprising a hanger on the tub, a leg having its upper end engaging with a curved portion on said tub, a tongue-plate on said leg having a portion in which the body of said hanger is located, and a member at 35 the free end of said plate extending upwardly and coöperating with said hanger.

2. A fastener for the legs of bath-tubs, comprising a hanger on the tub, a leg having its upper end engaging with a curved portion 45 on said tub, a tongue-plate on said leg having a portion in which the body of said hanger is located, a member at the free end of said plate extending upwardly and coöperating with said hanger, and means for connecting said hanger and plate together.

3. A fastener for the legs of bath-tubs comprising a hanger on the tub, a leg having its upper end engaging with a curved portion 55 on said tub, a tongue-plate on said leg provided with a portion therein in which the body of said hanger is located, a member at the free end of said plate extending upwardly and coöperating with said hanger,

and a tap-bolt passing through said plate and engaging with said hanger for connecting the same together. 60

4. A fastener for the legs of bath-tubs comprising a hanger on the tub, a leg having its upper end engaging with a curved portion on said tub, a tongue-plate on said leg 65 having a portion in which the body of said hanger is located, and integral stops at the free end of said plate extending upwardly and coöperating with said hanger.

5. A fastener for the legs of bath-tubs comprising a hanger on the tub, a leg having its upper end engaging with a curved portion on said tub, a tongue-plate on said leg 70 having a portion in which the body of said hanger is located, and stops at the free 75 end of said plate formed by the wall of said last named portion and extending upwardly and coöperating with said hanger.

6. A fastener for the legs of bath-tubs comprising a hanger on the tub, a leg having its upper end engaging with a curved portion on said tub, a tongue-plate on said leg 80 having a portion in which the body of said hanger is located, and stops at the free end of said plate and formed by cut-away 85 portions on the wall of said last named portion, said stops extending upwardly and coöperating with said hanger.

7. A fastener for the legs of bath-tubs comprising a hanger on the tub, a leg having 90 its upper end engaging with a curved portion on said tub, a tongue-plate on said leg having a portion in which the body of said hanger is located, a member at the free end of said plate extending upwardly and 95 coöperating with said hanger, and bearing portions on said hanger for engaging with the bottom of said last named portion.

8. A fastener for the legs of bath-tubs comprising a hanger on the tub, a leg having 100 its upper end engaging with a curved portion on said tub, a tongue-plate on said leg having a portion in which the body of said hanger is located, a member at the free end of said plate extending upward and coöperating with said hanger, bearing portions 105 on said hanger for engaging with the bottom of said last named portion, and means for connecting said hanger and plate together.

In testimony whereof I, the said WILLIAM H. LOSE, have hereunto set my hand. 110

WILLIAM H. LOSE.
